2 Claims. (Cl. 200—145)

This invention relates to electric switches of the kind comprising a switch pin which moves axially in a quenching chamber containing quenching medium and draws arcs which generate pressure in the quenching medium so that the latter is caused to flow past and quench the arcs.

The invention is intended to provide an improved switch of the kind referred to, arranged so that the arc or arcs are not drawn out to such an extent that the rise of pressure in the quenching medium is excessive. In some known switches excessive rise of pressure leads to rupturing of the quenching chamber.

According to the invention a switch of the kind referred to is characterised in that the switch pin comprises conducting parts and insulating parts, and fixed contacts and terminals are arranged so that in operation the conducting parts of the switch pin draw from the contacts arcs which are in series with one another and then the arcs move and burn in gaps between the terminals and are there subjected to the action of the quenching medium as the latter is flowing towards one or more outlets of the quenching chamber. Further and optional features of the invention appear from the following description and claims.

Two switches according to the invention are illustrated by way of example in sectional elevation in the accompanying drawing.

The switch shown in FIG. 1 comprises a quenching chamber 1 filled with quenching medium and accommodating fixed contacts, 2, 3, 4 and 5 and an axially-movable switch pin consisting of conducting parts 6 and 7 and insulating parts 8 and 9.

The switch pin slides axially in guides 10 and 11 in the quenching chamber 1.

The fixed contacts 3, 4 are connected to each other through a conducting tube 12 provided with terminals 14 and 15.

A fixed terminal 13 has an aperture forming an outflow opening for quenching medium in the quenching chamber 1, and also has an aperture in which the switch pin slides.

A fixed terminal 16 on the contact 5 is below a narrow passage 17 formed in an insulating mass, and this passage 17 is open through a slot 18 formed so that an arc between the contacts 4 and 5 can be guided to the terminals 15 and 16. The space accommodating the terminal 14 communicates through a slot 19 with the space between the terminal 2 and contact 3.

In order to compel the arcs drawn between the parts 2 and 3 and between the parts 4 and 5 to strike over on to the terminals 13, 14 and 15, 16 respectively, the spacing of the terminals from one another is less than that of the contacts 2, 3 and 4, 5.

The tube 12 constituting the connection between the contacts 3 and 4 contains a volume of quenching medium which is not subjected directly to heating by the arcs.

The guides 10 and 11 for the switch pin are always closed by the switch pin.

The switch is shown in the closed position, the path of the current being through the contact 2, the part 6, the contact 3, the tube 12, the contact 4, the part 7, and the contact 5.

On opening of the switch the switch pin moves upwards, and two arcs are drawn between the switch pin parts 6

2

and 7 and the fixed contacts 3 and 5. The roots of the arcs on the fixed contacts 3 and 5 immediately travel through the slots 19 and 18 to the terminals 14 and 16 respectively.

5 The two arcs now burn one between the switch pin part 6 and the terminal 14 and the other between the switch pin part 7 and the terminal 16.

On further movement of the switch pin, firstly the lower end of the switch pin part 6 comes into the vicinity of the terminal 13, so that the root of the arc burning on the switch pin part 6 jumps over on to the terminal 13 and the arc now burns between the terminals 13 and 14.

On further movement of the switch pin the lower end of the switch pin part 7 comes into the vicinity of the terminal 15 so that the root of the lower arc jumps to the terminal 15 and the arc burns between the terminals 15 and 16.

Pressure in the quenching medium is generated immediately on drawing of the arcs by the switch pin, and this pressure is maintained and built up to the desired maximum pressure values due to the length of the arc between the terminals 15 and 16.

Due to this pressure rise quenching medium flows past the terminal 15 and past the terminal 14 and out through the terminal 13, bringing about a reliable quenching of the arcs. The flow of quenching medium past the terminals 14 and 13 is very effective because it comprises quenching medium expelled from the tube 12 and not heated by the arc.

30 The switch pin part 7 comes into its end position in parallel with the tube 12, the guides 10 and 11 for the switch pin remaining closed.

Due to the arrangement of the switch pin the pressure rise in the quenching chamber can have no effect upon 35 the switch pin movement. Furthermore the quenching operation is not unfavourably influenced by the switch pin movement because after a specific time it is independent of the rate of switch pin movement.

30 Due to the pressure-generating arc burning with constant length between the terminals 15 and 16 an undesired pressure rise is prevented so that destruction of the quenching chamber is avoided.

The lengths of the switch pin parts can be such that the upper arc is struck later than the lower.

45 For the control of the issuing quenching medium the outflow opening of the quenching chamber can be provided with a valve which only opens at a predetermined pressure value.

Gas or liquid with or without inert powder can be used 50 as the quenching medium.

In FIGURE 2 fixed contacts 21, 22, 23, 24, 25 and 26 are arranged in a quenching chamber 20 filled with quenching medium and engage an axially-movable switch pin comprising conducting parts 27, 28 and 29 and insulating parts 30, 31 and 32.

The contacts 22 and 23 are electrically connected through a tube 34 and the contacts 24 and 25 are electrically connected through a tube 35.

55 The switch pin slides in guides 36 and 37 and closes these guides in every switch position.

Fixed terminals 38, 39, 40, 41, 42 and 43 are arranged so that the gaps between them are shorter than the corresponding gaps between the fixed contacts.

Arcs formed between the terminals 38 and 39 and 60 between the terminals 42 and 43 are quenched by the quenching medium issuing through outflow openings 44 and 45.

In the central gap between the terminals 40 and 41 is 65 formed an arc which serves for the pressure generation and is also subjected to the quenching action. For this purpose is provided a narrow channel 46 in order on the one hand to generate a very effective pressure rise and on

the other hand to subject the arc roots near the openings of the channel 46 on the terminals 40 and 41 to a very effective flow of quenching medium.

Spaces 47 and 48 inside the tubes 34 and 35 serve for the storage of quenching medium which is not directly contacted by the arcs.

For the guidance of the arcs from the switch pin to the terminals there are provided slots 50, 51 and 52 in an insulating body 53 which is provided with spaces and passages as shown. Conducting elements may be provided for facilitating the guidance of the arc roots from the switch pin and the fixed contacts to the terminals, and the terminals are advantageously placed close to the fixed contacts.

The switch is shown in the closed position, the path of the current being through the contact 21, the part 27, the contact 22, the tube 34, the contact 23, the part 28, the contact 24, the tube 35, the contact 25, the part 29, and the contact 26.

On the opening of the switch the switch pin is moved upwards and three arcs are drawn between the lower ends of the switch pin parts 27, 28 and 29 and the fixed contacts 22, 24 and 26.

The roots of the arcs initiated on the contacts 22, 24 and 26 immediately travel to the terminals 39, 41 and 43.

On further movement of the switch pin the upper root of the centre arc jumps on to the terminal 40, before the switch pin parts 28 and 29 have reached the contacts 22 and 24. In the end position the switch pin part 28 is in parallel with the tube 47.

The three arcs now burn between the terminals 38 and 39, between the terminals 40 and 41, and between the terminals 42 and 43. The middle arc between the terminals 40 and 41 generates a pressure rise which drives the quenching medium out of the spaces 47 and 48.

The pressure rise generated by the middle arc also serves, however, to expose this arc itself to an effective flow of quenching medium. Near the outlet openings of the narrow channel 46 are the terminals 40 and 41 on which the roots of the middle arc lie directly in the flow of the quenching medium issuing from the narrow channel 46.

The roots of all three arcs are exposed to effective currents of quenching medium, so that efficient quenching takes place.

It will be seen that in both the illustrated switches the quenching medium is forced through spaces in which the terminals are arranged and which converge so as to guide the medium effectively against the arcs. Each of the illustrated switches may be provided with one or more valves which permit the quenching medium to flow out of

the quenching chamber only when the pressure of the medium in the quenching chamber exceeds a predetermined value.

I claim:

1. An electrical switch of the kind in which arcs in series with each other are quenched by streams of quenching medium moving under pressure produced by the arcs themselves, comprising a quenching chamber containing quenching medium and having at least one outlet, a plurality of fixed contacts in said quenching chamber, at least one fixed conductor in said quenching chamber, each said fixed conductor interconnecting two of said fixed contacts, a plurality of arc terminals attached one to each end of each said fixed conductors, an axially-slidable switch pin extending through said quenching chamber in sliding contact with all of said fixed contacts, at least one insulating body forming slots and passages in said quenching chamber, each said slot affording communication between one of said passages and said switch pin and said passages leading to said arc terminals, and two switch pin guides secured one at each end of said quenching chamber, said switch pin consisting of insulating pin parts and conducting pin parts, the arrangement being such that in the closed condition of said switch a current path through said switch is completed by said fixed contacts and said conducting pin parts and said fixed conductors, during opening of said switch said conducting pin parts draw arcs which are in series with each other from said fixed contacts and said arcs travel through said slots and burn in said passages with roots on said arc terminals, said arcs being quenched by quenching medium flowing through said passages towards said outlets under pressure produced by the arcs themselves, and said switch pin in all its positions extends through and obturates both of said switch pin guides.

2. An electrical switch as claimed in claim 1, each said fixed conductor being of open-ended tubular form with an internal space accommodating quenching medium and communicating with two of said passages, the arrangement being such that under pressure generated by said arcs quenching medium from inside each said fixed conductor is forced into one of said passages.
